BRASSIÈRE FOR BATHING SUITS

Filed June 28, 1928

UNITED STATES PATENT OFFICE

ARTHUR J. BARNETT, OF NEW YORK, N. Y., ASSIGNOR TO THE WORCESTER KNITTING CO., OF WORCESTER, MASSACHUSETTS, A CORPORATION OF MASSACHUSETTS

BRASSIÈRE FOR BATHING SUITS

Application filed June 28, 1928. Serial No. 288,888.

This invention relates to a bathing suit. The principal object thereof is to provide it with a convenient form of brassière. Also to provide a brassière in two pieces which 5 may be connected together or not and to provide each of these pieces in a form in which it is attached at the top and bottom so that it will stay in place and cannot slip down in front, to locate the attachment at the top at a 10 point well above the usual brassière and also at the bottom at a point below it, and more specifically to connect it with the shoulder strap at the top and the waistline at the bottom, and to provide a construction which will 15 not slip down in front and will not be visible in the front of the suit.

Other objects and advantages of the invention will appear hereinafter.

Reference is to be had to the accompanying 20 drawings in which

Fig. 1 is a front view of a bathing suit constructed in accordance with this invention;

Fig. 2 is a rear view of the front of the bathing suit from the inside, and

Fig. 3 is a horizontal sectional view on the line 3—3 of Fig. 2.

Bathing suits have been provided with brassières heretofore which have been made in imitation of the ordinary brassière and 30 consequently had to be fastened at the sides under the arms. This did not provide for keeping them in place or else they had to be secured to the body of the suit which might show on the front. In this invention the front 35 of the bathing suit as shown in Fig. 1 gives no indication of the presence of a brassière and, as will be seen, after long wear it will not show in the front in any way.

Referring particularly to Figs. 2 and 3, it 40 will be seen that the bathing suit which is made of knitted material and is elastic transversely, is provided on the inside of the front with two pieces of cloth 10, which preferably are non-elastic, each one having a vertical gathering seam 11 and 12 at the top and bottom respectively for making them concave in shape. These two pieces are entirely separate 45 but I have shown them as connected at one point by a knitted, and therefore transversely

elastic, piece of material 14 sewed to the inner adjacent edges.

These two pieces 10 are secured to the bathing suit at the top and bottom. The method of securing them at the top is shown as in the 55 form of the hemming seams on the front and near the edges of the shoulder straps and extending at the front down to the horizontal portion of the neck part of the garment and at the rear to a point under the arms. It 60 will be seen therefore that they are thoroughly covered at the top so as to be invisible and will not become detached or loosened in wear so as to show. At the bottom each one is provided with a downwardly extending portion 65 16 which is secured by a horizontal seam 17 at or near the waist line.

Each one of these pieces acts practically independently of the other. In this way the natural elasticity of a garment transversely 70 is not interfered with in any way. If the garment is stretched, the two parts of the brassière move apart with it and whether they are connected at the center or not, they do not materially restrict the action of the wearer in 75 putting the garment on or in bending over or twisting. The two parts always come back to the proper position and are always in place to perform the desired function. At the same time they are securely fastened at both top 80 and bottom and receive the entire support along a substantially vertical line. They are more comfortable for the wearer and leave the bathing suit in suitable condition of elasticity for wear and no important strain is 85 put upon them when the suit is put on or taken off.

The two parts of the brassière are free from the material of which the bathing suit is 90 formed at all points within the outline of the same, being fastened only around the edges and at the single point near the waist and yet they are firmly secured in place as stated. There is no danger of their slipping down out of place or getting into a position 95 in which they are visible from the front.

Although I have illustrated and described only one form of the invention I am aware of the fact that modifications can be made therein by any person skilled in the art with- 100

out departing from the scope of the invention as expressed in the claims. Therefore, I do not wish to be limited to all the details of construction herein shown, but what I do claim is:—

- 5 1. As an article of manufacture, a bathing suit having a waist portion provided with shoulder straps and a nether portion and a brassière connected with the waist portion at the top and bottom to insure that any strain applied to the brassière will be along substantially vertical lines.
- 10 2. As an article of manufacture, a bathing suit formed of knitted material comprising a waist portion having shoulder straps and a nether portion and provided with a bust supporter consisting of two separate pieces of non-elastic fabric each one independently secured to the waist portion at the shoulder straps and at the waist line only.
- 15 3. As an article of manufacture, a bathing suit having a brassière secured at its top to the shoulder portion of the suit and at its bottom to the waist region of the suit and free from the material and located inside of the bathing suit at all intermediate points.
- 20 4. As an article of manufacture, a bathing suit supplied with a brassière attached to the bathing suit along the hemmed edges of the shoulder straps and at a point near the waist line and having two central vertical seams at the top and bottom respectively to make the same concave to provide fullness in the area between the said seams.
- 25 35 In testimony whereof I have hereunto affixed my signature.

ARTHUR J. BARNETT.
